(57) **CLAIM**

I claim the ornamental design for a double deck feeder for wild animals, as shown and described.

DESCRIPTION

FIG. 1 is an upper front perspective view.

FIG. 2 is an upper rear perspective view.

FIG. 3 is a lower front perspective view.

FIG. 4 is a front elevation view.

FIG. 5 is a rear elevation view.

FIG. 6 is a top plan view.

FIG. 7 is a bottom plan view.

FIG. 8 is a right side elevation view.

FIG. 9 is a left side cross-section elevation view taken at line 9-9 in FIG. 6.

FIG. 10 is an upper front perspective environmental view.

FIG. 11 is a right side elevation view portraying a middle shelf in a higher alternate position; and,

FIG. 12 is a right side elevation view portraying the middle shelf in a lower alternate position.

Broken lines form no part of the claimed design and represent the unclaimed environment.

1 Claim, 10 Drawing Sheets
